SWING

Daniel B. Sullivan, Portland, Conn.

Application August 21, 1935, Serial No. 37,173

4 Claims. (Cl. 155—65)

My invention relates to that type of amusement devices which are suspended to support a person for swinging movement, and an object of my invention, among others, is to provide an amusement device of this kind which shall be attractive, which will be highly amusing in its operation and the sensation produced thereby, and which also is provided with means for effecting swinging movement.

10 One form of a swing embodying my invention and in the construction and use of which the objects herein set out, as well as others, may be attained is illustrated in the accompanying drawing in which

15 Figure 1 is a view in side elevation of my improved swing shown in its normal position.

Figure 2 is a similar view illustrating the manner of effecting swinging movement of the support.

20 Figure 3 is a top view of the support on enlarged scale.

Figure 4 is a side view of the same.

In the accompanying drawing a supporting frame is illustrated from the top of which the swing is suspended, this frame comprising corner strips 5, base pieces 6, top rails 7 and bracing pieces 8 all of which may be arranged in any suitable manner to afford a suitable support for the swing. In that particular form of device herein illustrated and described a rocker is suspended from flexible supports, this rocker, as herein shown, being in the form of an animal, as a horse, including a body 9, upon which a saddle 10 may be placed and which may be termed a seat carrier. The head 11 is movably connected with the body as by means of a link or links 12, as herein shown there being two of these links located on opposite sides of a projection or tang 13 extending forwardly from the neck 15 of the animal, these links being pivotally connected to the projection at their lower ends and also similarly attached to a projection or tang 16 from the head 11, and as shown in Figs. 3 and 4 of the drawing. Elastic head positioning members may be employed for keeping the head 11 in its normal position, one of these members 17 extending from underneath the head to the top of the neck and the other member 18 extending from the top of the head to the front or breast portion of the animal, and as shown in Fig. 4 of the drawing.

50 The body 9 will hang normally suspended, as shown in Fig. 5 of the drawing, but if displaced from this position the tendency will be to again assume its normal position, and this will cause

a swinging action. To effect such action a displacing member 19 is provided as herein shown this being in the form of reins, the reins being attached as to an arm 20 extending from the jaw of the animal and which may resemble a portion 5 of a bit.

The suspension devices or suspenders for the body 9 comprise bails 21—22 pivotally attached to the head and rear end of the body preferably on opposite sides thereof. Stiff elastic members 10 23—24 are attached at their lower ends, respectively, to the bails 21 and 22, the upper ends of the elastic members being fastened to the lower ends of cords 25—26, the upper ends of the cords being secured to the top of the frame preferably 15 at the widthwise center thereof.

The bail 22 is secured to a shaft 27 projecting through the rear end of the body, and a tail 28 is secured at one end to said shaft, said tail projecting out of the rear end of the body to any suitable extent, and as shown in Figs. 3 and 4 of the drawing.

20 Stirrups 29 may be suspended from the saddle 10 in which stirrups the feet of the rider may be placed, and bracing of the body of the rider 25 against the stirrups will aid in promoting the swinging action of the body.

In operation a pull upon the reins or displacing member 19 will pull the head backwardly causing the body 9 to move forwardly out of its normal position, and the force of the pull being released the body in its tendency to assume its normal position will pass beyond such position to the rear thereof. At this time another pull upon the reins will move the body forwardly to a point beyond that first attained and this action being repeated the swinging movement may be accelerated to any extent. The elastic suspension devices 23 and 24 provide a yielding support enabling an up and down movement to be obtained somewhat resembling the action of a moving horse. It will be understood that the suspension members 23—24, as well as the members 17—18, consist of stiff elastic material which may be readily obtained and of a strength sufficient for 45 the purpose herein set out.

50 In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim:

1. A swing including a pair of suspenders, an elongated seat carrier supported by the suspenders for swinging movement in the plane of the suspenders, one of the suspenders being directly attached to the rear end of the seat carrier, an actuator to effect swinging movements of the seat carrier including a pair of pivotally connected members, one of the members being pivotally attached to the forward end of the seat carrier and the other member being pivotally attached to the other suspender, and a pull device carried by the member attached to the suspender at a point forwardly of the point of attachment of said member to the suspender and disposed in a plane below the pivotal connection between the two members with actuating force on the pull devices exerted in a direction towards the rear end of the seat carrier.
2. In a swing, a pair of suspenders supported at their upper ends for swinging action, an elongated seat carrier supported by the suspenders for swinging movement in the plane of the suspenders, one of the suspenders being directly attached to the rear end of the seat carrier, and an actuator to effect swinging movements of the seat carrier including a member pivoted to the forward end of the seat carrier, a second member pivoted to the aforesaid member with the other suspender pivotally attached to the second member, and manually operable means attached to the second member outwardly of the pivotal connection between the two members and below the pivotal con-

nexion between the second member and suspender for effecting pivotal movements of the two members on the seat carrier and swinging movements of the seat carrier.

3. A swing including suspenders supported at their upper ends for swinging action, a narrow rigid body having a tang at one end, a seat in the body, links pivotally secured to opposite sides of said tang, a head pivotally attached to said links for pivotally supporting the head member 10 on the body member, said head member and opposite ends of the body member respectively being attached to the suspenders and manually operable means attached to the head member for effecting pivotal movement thereof on the body 15 member and swinging movement of the body and head members.

4. A swing including suspenders supported at their upper ends for swinging action, a narrow rigid body having a tang projecting from one end, 20 a seat on the body, links pivotally attached to opposite sides of said tang, a head having a tang at its rear side projecting in the space between said links and pivotally secured therein for pivotally supporting the head member on the body 25 member, said head member and opposite end of the body member respectively being attached to the suspenders and manually operable means attached to the head member for effecting pivotal movement thereof on the body member and 30 swinging movement of the body and head members.

DANIEL B. SULLIVAN.
